FISH FEEDER PACKAGE

Allan H. Willinger, 56 Gail Drive,
New Rochelle, N.Y. 10805

Filed July 27, 1967, Ser. No. 8,017

Term of patent 14 years

Int. Cl. D9—04

U.S. Cl. D9—193

FIGURE 1 is a front elevational view of a fish feeder package, showing my new design;

FIGURE 2 is a view, in exploded form, showing the component parts thereof in elevation;

FIGURE 3 is a top plan view of the top cover of the container viewed in the direction of arrows 3—3 of FIGURE 2;

FIGURE 4 is a top plan view of the dispenser member as viewed in the direction of arrows 4—4 of FIGURE 2;

FIGURE 5 is a top plan view of the inside lid member as viewed in the direction of arrows 5—5 of FIGURE 2;

FIGURE 6 is a bottom plan view of the bottom cover of the container viewed in the direction of arrows 6—6 of FIGURE 2.

The broken line indication of fish food is shown for illustrative purposes.

I claim:

The ornamental design for a fish feeder package, substantially as shown and described.
